DOOR CHECK STRUCTURE

Paul H. Travis, Leonard, and Howard M. Davidson, Detroit, Mich.; said Davidson assignor to said Travis.

Application April 7, 1947; Serial No. 739,742.

10 Claims. (Cl. 16—86)

1

This invention relates generally to door check structures and refers more particularly to concealed type structures having means for releasably holding or retaining the door in open position so that it will not accidentally swing toward closed position after being checked.

One of the essential objects of the invention is to provide a door check structure wherein a rigid elongated arm carries both the means for checking the opening swinging movement of the door and the means for holding or retaining the door in its open position.

Another object is to provide a door check structure wherein the rigid elongated arm is movable lengthwise through a closed loop within and rigid with the hinge pillar during both opening and closing swinging movement of the door. The means for checking the opening swinging movement of the door is engageable with a support for said loop when the door reaches a predetermined open position. The means for holding or retaining the door in said open position is operable to spring outwardly over opposite side portions of said loop and then snap inwardly into gripping engagement with opposite sides of said elongated arm beyond said loop when the door is checked in said open position.

Another object is to provide a door check structure wherein the door checking means and door holding means operate independently of one another to perform their respective functions.

Another object is to provide a door check structure wherein the checking means includes a resilient element for cushioning or absorbing the shock of checking the opening movement of the door.

Another object is to provide a door check structure wherein the holding or retaining means includes a yieldable brake operable in advance of said checking means to slow up the opening movement of the door before it is checked.

Another object is to provide a door check structure that is operable without rattling or setting up objectionable noises.

Another object is to provide a door check structure that is strong and durable and is capable of withstanding without injury thereto the shocks and strains to which it is subjected while in use.

Another object is to provide a door check structure that is simple in construction, economical to manufacture, easy to install, and efficient in operation.

Other objects, advantages and novel details of construction of this invention will be made more apparent as this description proceeds, especially when considered in connection with the accompanying drawings, wherein:

Fig. 1 is a fragmentary horizontal sectional view through a swinging door, supporting hinge

2

pillar therefor and door check structure embodying our invention, and showing the arrangement of parts when the door is in its fully opened checked position;

Fig. 2 is a view similar to Fig. 1 but showing the door in fully closed position;

Fig. 3 is a fragmentary vertical sectional view through the hinge pillar, reinforcement and door check structure when the door is in open position as illustrated in Fig. 1;

Fig. 4 is a view similar to Fig. 3 but showing the position of parts when the door is in partially open position;

Fig. 5 is a sectional view taken substantially on the line 5—5 of Fig. 2;

Fig. 6 is an elevational view of a slight modification;

Fig. 7 is a sectional view taken on the line 7—7 of Fig. 6;

Fig. 8 is an end view of the construction illustrated in Figs. 6 and 7;

Fig. 9 is a fragmentary elevational view of another modification;

Fig. 10 is a sectional view taken on the line 10—10 of Fig. 9;

Fig. 11 is an elevational view of a modified form of mounting for the closed loop;

Fig. 12 is an end view of the structure illustrated in Fig. 11;

Fig. 13 is a view similar to Fig. 11 but showing another modification;

Fig. 14 is an end view of the construction illustrated in Fig. 13;

Fig. 15 is a fragmentary elevational view of a further modification;

Fig. 16 is an end view of the construction illustrated in Fig. 15.

Referring now to the drawings, A is the rigid elongated arm, B is the door check means, and C is the combination brake and retaining means of a combination door check and retainer embodying our invention.

As shown, the arm A is a substantially flat metal stamping provided at one end with an opening 10 for a pivot pin 11 and provided at its other end with a segmental head 12. Preferably the portion 13 of the arm A containing the opening 10 is wider than the arm proper and forms an enlargement, while the head 12 of the arm is likewise wider than the arm proper and forms an abutment.

The door check means B comprises a cushioning element 15 and a backer 16 therefor. As shown, the cushioning element 15 consists of a cylindrical body of rubber or rubber composition and is sleeved upon the arm adjacent the head 12, while the backer 16 for said cushioning element is preferably formed of metal and is sleeved on said arm between the cushioning element 15 and the head 12 of the arm. Preferably the cross

sectional area of the enlargement 13 of the arm is such that the cushioning element 15 and backer 16 therefor may be slipped over the enlargement 13 to assembled position beside the head 12.

The combination brake and retaining means C comprises two spring metal strips 17 and 18, hereinafter referred to as retention strips, that are identical in construction and are disposed upon and extend longitudinally of opposite sides of the arm A. In Figs. 1 to 4 inclusive such retention strips 17 and 18 are riveted at one end to the head 12 of the arm and extend through the cushioning element 15 and backer 16 therefor. Preferably these retention strips 17 and 18 are provided at the outer face of the cushioning element 15 with outwardly arched or bulging portions 19 and 20 and have longitudinally curved end portions 21 and 22 that grip or bear firmly against opposite sides of the arm A in longitudinally spaced relation to the cushioning element 15.

In the present instance we have shown our door check structure in combination with a door D and a hollow hinge pillar E of a motor vehicle. However, it is to be understood that such a door check structure may be used with any form of swinging door and its supporting pillar. As shown, the door check arm A extends substantially horizontally from the door D through a suitable opening 23 in the adjacent wall 24 of the hinge pillar E. The pivot pin 11 for the arm A is carried by two vertically spaced angle plates 25 fixed to the upright 26 of the door, while the head 12, cushioning element 15, backer 16 and retention springs 17 and 18 are within the pillar E.

27 is a substantially channel shaped reinforcement for the pillar E and is disposed within the latter. Preferably this reinforcement 27 has lateral flanges 28 and 29 secured to the wall 24 thereof. 30 is a closed elongated loop type metal guide that is riveted directly to the base 31 of the channel reinforcement in registry with an enlarged opening 32 therein. When the parts are assembled the arm A extends through the loop 30, while the retention springs 17 and 18 extend over or straddle said loop.

In use, when the door D is moving toward a predetermined open position, the curved end portions 21 and 22 of the retention strips will first engage the adjacent edges 33 and 34 of the loop 30 to initially slow up or retard such opening movement of the door. During continued opening movement of said door, the curved end portions 21 and 22 of the retention springs will be forced laterally outward by the opposed parallel side portions 35 and 36 of the loop so that said end portions 21 and 22 will ride over said side portions to points beyond the same where the said end portions 21 and 22 will snap inwardly against opposite sides of the arm A to effectively hold the door against accidental closing movement. At about the time the end portions 21 and 22 of the retention springs snap against the arm A as aforesaid, the cushioning element 15 will abut the base 31 of the reinforcement 27 to check the opening movement of the door. Thus, the door will be effectively checked and held in open position. In this connection it will be noted that the cushioning element 15 is upon one side of the base 31 of the reinforcement for checking movement of the door in one direction, while the end portions 21 and 22 of the retention springs are upon the other side thereof for checking movement of the door in the opposite direction when the door is in its fully opened checked position. Both the cushioning element 15 and the reten-

tion springs 17 and 18 are carried by the arm A and move therewith during movement of the door. It should also be noted that the outwardly arched portions 19 and 20 of the retention springs 5 effectively hold the cushioning element 15 against its backer 16. By referring to Figs. 4 and 5 it will also be noted that the cushioning element 15 and backer 16 cooperate with the rivet 37 to hold the retention springs 17 and 18 under compression against opposite sides of the arm A.

In Figs. 6 to 8 inclusive we have illustrated a slight modification wherein the retention springs 40 and 41 upon opposite sides of the arm A are connected beyond the adjacent end 42 of 15 said arm by an integral U-shaped portion 43 which straddles said end portion. In this form a cotter pin 44 extends through aligned openings in the arm A and retention springs 40 and 41 in 20 rear of the metal backer 45 for the cushioning element 46 to retain the parts in assembled relation. Otherwise the construction and operation of the parts are the same as in Figs. 1 to 4 inclusive.

In Figs. 9 and 10 we have illustrated another 25 modification wherein the retention springs 50 and 51 upon opposite sides of the arm A are connected by an integral U-shaped portion 52 which straddles the adjacent end 53 of the arm, but separate securing elements such as rivets and/or cotter pins similar to those used in the constructions 30 previously described have been dispensed with entirely. In this modification portions 54 and 55 of the retention springs 50 and 51 are pressed inwardly within an opening or hole 56 in the arm 35 A so as to abut an edge of said opening, while other portions 57 and 58 of said springs are pressed outwardly so as to abut the adjacent rear face of the metal backer 59 for the cushioning element 60. Thus the U-shaped portion 52 cooperates with the inwardly pressed portions 54 and 55 just mentioned to hold the retention springs 50 and 51 against displacement from the arm A, and the portions 57 and 58 cooperate with the arched portions 19 and 20 to hold the cushioning element 60 and backer 59 in assembled relation with respect to said springs 50 and 51 and arm A. Otherwise the construction and operation of parts are the same as in Figs. 1 to 4 inclusive.

In Figs. 11 and 12 we have illustrated another 50 modification wherein the closed elongated loop 70 is riveted to a separate retainer plate 71 which in turn may be riveted to the base 31 of the reinforcement for the pillar. The loop 70 is in registration with an enlarged opening 72 in the retainer plate 71. Thus, the retention springs 17 and 18 may move through the opening 72 in the plate 71, while the arm A is moving in the closed loop 70.

In Figs. 13 and 14 we have illustrated another 60 modification wherein an elongated substantially U-shaped metal strap 80 is carried by spaced lugs 81 and 82 of a retainer plate 83. In this construction the legs 84 and 85 of the U extend through and cooperate with the lugs 81 and 82 to form a 65 closed loop for the reception of the arm A. The opening 86 left by the lugs 81 and 82 after they are struck out corresponds to the opening 32 and is adapted to receive the retention springs 17 and 18 when the arm A moves through the loop.

In Figs. 15 and 16 the arm A has a shoulder 90 like the shoulder 14 but lacks a head such as 12. In this construction the retention springs 91 have complementary heads 92 which serve as stops for the cushioning element 93 and its back- 70 ing plate 94.

5

In all forms shown herein the base 31 of the reinforcement constitutes an abutment for the cushioning element B and is provided with an opening such as 32 or its equivalent for the reception of the arm A and parts carried thereby. In each instance the cushioning element is preferably made of rubber or rubber composition, however it is apparent that such element may be made of any suitable material for yieldably cushioning the opening movement of the door. Likewise, the backers such as 16 may be formed of any suitable material to serve efficiently as backers for the cushioning elements. The arms A are preferably metal stampings, however they too may be any other material having sufficient strength to function properly in the capacity for which they are designed.

What we claim as our invention is:

1. In a door check structure, an elongated rigid arm provided adjacent one end thereof with a hole for a pivot element and provided adjacent its other end with an opening, elongated spring metal strips upon opposite sides of and extending longitudinally of said arm, portions of said strips being struck therefrom into said opening, a connection between said strips straddling said other end of said arm and cooperating with said struck portions to hold said strips against movement longitudinally of said arm, and a resilient cushioning element and backer therefor having registering openings receiving said arm and strips, portions of said strips being struck therefrom to serve as abutments for said backer, and other portions of said strips being arched in advance of said element and normally cooperating with said last mentioned struck portions to hold said element and backer against movement longitudinally of said arm, said last mentioned arched portions being compressible toward said arm to permit movement of said element and backer to and from said abutments.

2. In a door check structure, an elongated rigid arm having an opening therein, a resilient cushioning element and a metal backer therefor sleeved upon said arm, elongated retention springs upon opposite sides of and extending longitudinally of said arm, said springs being connected at one end by a U-shaped portion straddling the adjacent end of said arm, and means holding said springs, cushioning element and backer in assembled relation with said arm, including portions of said springs pressed inwardly within the opening in said arm and abutting an edge thereof, and other portions of said springs pressed outwardly and abutting the adjacent rear face of said backer.

3. In a door check structure, an elongated rigid arm having an opening therein, a resilient cushioning element and a backer therefor sleeved upon said arm, retention springs upon opposite sides of and extending longitudinally of said arm, said springs being connected at one end, and means holding said springs, cushioning element and backer in assembled relation with said arm, including portions of said springs pressed inwardly within the opening in said arm and abutting an edge thereof, and other portions of said springs pressed outwardly and abutting said backer.

4. In a door check structure, an elongated rigid arm having an opening therein, a resilient cushioning element and a backer therefor sleeved upon said arm, a retention spring upon one side of and extending longitudinally of said arm, and

6

means holding said spring, cushioning element and backer in assembled relation with said arm, including a portion of said spring pressed inwardly within the opening in said arm and abutting an edge thereof, and another portion of said spring pressed outwardly and abutting the adjacent rear face of said backer.

5. In a door check structure, an elongated rigid arm having an opening therein, an abutment member on said arm, and means for holding said member against displacement, including a strip extending longitudinally of said arm and having portions overlapping opposite sides of said member, one of said portions being struck outwardly from said strip and engaging said abutment member, and another of said portions engaging the opening in said arm.

6. In a door check structure, an elongated rigid arm, an abutment member on said arm, and means for holding said member against displacement including elongated spring metal strips upon opposite sides of said arm and extending through said member, portions of said strips overlapping opposite sides of said member, said arm having an opening therein, portions of said strips being struck therefrom into said opening, and a connection between said strips engaging an end of said arm.

7. In a door check structure, an elongated rigid arm having an opening therein, a strip extending longitudinally of said arm, an element encircling said arm and strip, means holding said strip against displacement, including a portion of said strip engaging said opening, and means holding said element against displacement, including another portion of said strip engaging said element.

8. In a door check structure, an elongated rigid arm having an opening therein, a strip extending longitudinally of said arm, an element encircling said arm and strip, means holding said strip against displacement, including an inwardly pressed portion of said strip engaging said opening, and means holding said element against displacement, including an outwardly pressed portion of said strip engaging said element.

9. In a door check structure, an elongated rigid arm having an opening therein, an element encircling said arm, and means for holding said element against displacement, including a strip extending longitudinally of said arm and having oppositely projecting portions respectively engaging said opening and said element.

10. In a door check structure, an elongated rigid arm, an element encircling said arm, and means for holding said element against displacement, including a strip extending longitudinally of said arm and having two oppositely pressed portions, one of said portions being pressed inwardly for abutting engagement with a part of said arm, and the other of said portions being pressed outwardly for abutting engagement with said element.

PAUL H. TRAVIS.
HOWARD M. DAVIDSON.
